UNITED STATES PATENT OFFICE.

GUSTAF REINHOLD SANDELL, OF NEW YORK, N. Y., ASSIGNOR TO THE
EAGLE PENCIL COMPANY, OF SAME PLACE.

LEAD AND CRAYON HOLDER.

SPECIFICATION forming part of Letters Patent No. 340,925, dated April 27, 1886.

Application filed March 23, 1886. Serial No. 196,217. (No model.)

To all whom it may concern:

Be it known that I, GUSTAF REINHOLD SANDELL, of the city, county, and State of New York, have invented certain new and useful 5 Improvements in Lead and Crayon Holders, of which the following is a specification.

The lead and crayon holder in which my invention is embodied is of the "stop gage" type, and is one in which the lead-grasping 10 device is operated at or near the conclusion of its forward movement (or movement in the direction necessary to release the lead) to close sufficiently to intercept or check the lead at the time when the point of the latter projects 15 a predetermined distance beyond the tip or front end of the holder. A stop-gage holder possessing this characteristic is not new with me, broadly considered, one form of the same being disclosed in Letters Patent No. 265,730, 20 of October 10, 1882. In said patented device is also a lead-detent which retains the lead until the lead-grasping device has advanced and closed in its stop-gage position, and which then opens and releases the lead and allows the latter to fall as far as permitted by the stop-gage. 25

The holder in which my invention is comprised contains both of these devices. The lead-grasping device consists of longitudinally-movable spring-controlled jaws which normally stand apart, like the jaws of the ordinary 30 automatic pencil. The lead detent or retaining device consists of a split collapsible nozzle arranged within or between the jaws and fast to the sheath or case of the holder, so that the jaws can move longitudinally with reference to it. In the jaws, at proper points in rear of their grasping ends, are formed slots into which fingers or pressers extend, said fingers or pressers being fast to some part (such 35 as the sheath or the nozzle) with reference to which the jaws are longitudinally movable, and the arrangement being such that normally, or when the jaws are retracted, said fingers or pressers shall occupy such a position as to exert no appreciable closing-pressure upon the 40 jaws, but that when the jaws are protruded the fingers or pressers shall bear externally from opposite sides upon the jaws or the jaw-stems, and thus cause the jaws to close in their 45 stop-gage position. The pressers or fingers 50

are used also to cause or permit the proper action of the lead detent or collapsible nozzle, it being requisite that the detent or collapsible nozzle should remain closed while the jaws are moving forward to stop-gage position, and 55 should then open to allow the lead to drop.

The nature of my improvement and the manner in which the same is or may be carried into effect will be readily understood by reference to the accompanying drawings, in 60 which—

Figure 1 is a vertical central section, partly in elevation, of a holder embodying my invention in its preferred form, the lead being represented in retracted position. Fig. 2 is a 65 similar section with the parts in the position which they assume when the jaws are half-way protruded. Fig. 3 is a like section with the jaws fully protruded and in stop-gage position. Fig. 4 is a like section with the lead 70 protruded and grasped by the jaws. Fig. 5 is a perspective view of the front ends of the jaws and the collapsible nozzle. Figs. 6 and 7 are longitudinal sectional views of a modification, which will be hereinafter more particularly referred to. 75

A is the sheath or handle, terminating in the usual tip or nozzle, a.

B is the tube, corresponding to the lead-receiving tube of the ordinary "automatic" pencil, and, like that tube, terminating at its front end in spring-controlled grasping jaws b, which normally stand apart and are caused, when the lead-tube is retracted, to close upon the lead by the pressure of the tip or nozzle upon their 85 swells or inclines b'.

C is the pressure-cap, and D is the retracting-spring.

The parts thus far described, in so far as they co-operate for the purpose of grasping 90 and releasing the lead, do not differ materially from the like parts of the automatic pencil.

The lead detent or retaining device consists, in the present instance, of a split collapsible nozzle, e, which is arranged within the jaw-tube B, and by a pin, x, passing through a slot, y, in the jaw-tube, is so connected with the sheath or handle as to be incapable of following the longitudinal movement of the jaws. 95

In each jaw, a proper distance in rear of its 100

acting end, is a longitudinal slot, *d*, at the rear end of which is the shoulder *d'*, which is to be pressed at the time the jaws are fully protruded, in order to close them in stop-gage position. The fingers or pressers to act on these shoulders are seen at *e*. Two different arrangements of them are shown. In Figs. 1 to 5, inclusive, they are represented as consisting of rearwardly-extending prongs on the collapsible nozzle, which project up through the slots *d*. At the points where these prongs join the collapsible nozzle they are somewhat inclined on that face which adjoins the shoulder *d'*, as seen at *e'*, and said part *e'* is so located with reference to the part *d'* that when the jaws have reached their protruded position the faces *e'* will have pressed upon the shoulders *d'* sufficiently to force together or close the jaws. Indeed, in this arrangement the action of the jaws and the nozzle is reciprocal, for the same instrumentalities which cause the jaws to close will also cause the split or collapsible nozzle (which in Figs. 1 to 5 normally closes) to open.

The mode of operation of the holder in Figs. 1 to 5 is as follows: The parts are shown in Fig. 1 in the position they occupy when the lead is retracted. To protrude the lead, the pencil is held point downward and the pressure-cap is pushed forward, thus advancing the jaws, which open or release the lead while the collapsible nozzle clasps the lead, with sufficient firmness to hold it from dropping, all as indicated in Fig. 2. This condition of affairs continues until the jaws are fully protruded, at which time, by the action of the parts *d' e'*, the jaws will have been closed to stop-gage position, the collapsible detent or nozzle will have opened enough to release the lead, and the lead will have dropped as far as permitted by the jaws, as indicated in Fig. 3. The pressure-cap being released, the jaws at once return to position, the lead being held during their return by the collapsible nozzle, and the jaws opening so as to pass the lead without drawing it back until they bring up against the tip *a*, and are thereby closed upon the lead tightly.

In the arrangement shown in Figs. 6 and 7 the fingers or pressers *e*, instead of being carried by the collapsible nozzle, are attached directly to the interior of the case or sheath, and they have a slight spring action. Their acting ends *e'* normally stand in the slots *d*, and bear from opposite sides upon the split

nozzle *c*. The light spring-jaws of the nozzle in this arrangement are not normally spring-closing, as in the one just above described, but, on the contrary, are set so as to normally stand apart far enough not to press upon the lead. So long as the pressers *e* are in the slots *d* they bear upon and close the split nozzle, as seen in Fig. 6. When, however, the jaws are fully protruded, as seen in Fig. 7, the pressure of the parts *e* is transferred from the split nozzle *c* to the shoulders *d'* of the jaws, thus closing the latter into stop-gage position, and permitting the former to open and allow the lead to drop.

I am aware that it is not new to use in a lead and crayon holder two sets of grasping devices which act upon one another in such manner that the opening of the one set causes the other set to close, and this I do not broadly claim.

Having now described my improvement and the best way known to me of carrying the same into effect, I desire to be understood, in conclusion, that I do not restrict myself to the details of construction and arrangement hereinbefore set forth, for the same obviously can be varied considerably without essential departure from the principle of my invention; but

What I claim herein as new is—

1. The combination of the sheath or handle, the collapsible or split nozzle, the longitudinally-movable spring-controlled and normally-open lead-grasping jaws, provided each with a longitudinal stop gage slot and shoulder, and the arms or pressers arranged and adapted to bear externally upon the jaws and to operate in connection with said slots and shoulders, substantially in the manner and for the purposes hereinbefore set forth.

2. The combination of the sheath or handle, the collapsible or split nozzle, the longitudinally-movable lead-grasping jaws provided each with a longitudinal stop-gage slot and shoulder, and rearwardly-extending arms or prongs fast to the split nozzle, projecting into and through said slots and arranged and adapted to operate in connection with said shoulders, as and for the purposes hereinbefore set forth.

In testimony whereof I have hereunto set my hand this 19th day of March, 1886.

GUSTAF REINHOLD SANDELL.
